UNITED STATES PATENT OFFICE

AMOS A. WYCKOFF AND BERNICE L. YAUNAY, OF OAKLAND, CALIFORNIA

DESIGN FOR A GARMENT HANGER

Application filed July 22, 1931. Serial No. 40,636. Term of patent 7 years.

To all whom it may concern:

Be it known that we, AMOS A. WYCKOFF and BERNICE L. YAUNAY, both citizens of the United States, and residents of Oakland, in the county of Alameda and State of California, have invented a new, original, and ornamental Design for a Garment Hanger, of which the following is a specification, reference being had to the accompanying drawings, forming part thereof.

We claim:

The ornamental design for a garment hanger substantially as shown.

AMOS A. WYCKOFF.

BERNICE L. YAUNAY.
